WICK-RESTRICTING MEANS.

1,330,845.

Specification of Letters Patent. Patented Feb. 17, 1920.

Application filed May 9, 1918. Serial No. 233,485.

To all whom it may concern:

Be it known that I, LEE S. CHADWICK, a citizen of the United States, residing at East Cleveland, in the county of Cuyahoga and State of Ohio, have invented a certain new and useful Improvement in Wick-Restricting Means, of which the following is a full, clear, and exact description, reference being had to the accompanying drawings.

10 This invention pertains to the class of liquid fuel burners wherein wicks are used; and relates particularly to means for restricting the wick against withdrawal from the oil supply.

15 In oil stoves and lamps, particularly of the sort wherein tubular wicks are employed, it has been found that especially when the wick is comparatively long, as when new, and is turned down into contact with the 20 bottom of the oil reservoir, the opposite sides of the lower end of the wick—for it may be explained that tubular wicks are split upward some distance from their lower ends, usually at diametrically opposite points—become spread out and, when the wick is subsequently turned up, the flared sides retain 25 their spread out condition and lift bodily out of the oil so that instead of the oil being conducted through the wick to satisfy the 30 flame, the wick itself is burned away.

It is the fundamental purpose of my invention to provide means for restricting a portion of the wick at all times in proximity to the bottom of the oil reservoir so that it 35 may receive a supply of fuel as long as any remains within the reservoir; and further objects are to provide a simple and very effectual device for fulfilling the foregoing purpose and which is economical of manufacture and convenient of incorporation in oil burners of prevailing styles.

In the accompanying drawing wherein I have illustrated an embodiment of my invention, Figure 1 is a vertical section 45 through an oil burner equipped with my wick restricting means; Fig. 2 is a section on the line 2—2 of Fig. 1, looking upward; and Fig. 3 is a perspective of the restricting means removed from the burner.

50 The oil burner wherein I have shown my restricting means incorporated for the purpose of illustration is of standard type and comprises a reservoir 1; an inner wick tube 2 which rises centrally of the reservoir and 55 opens through the bottom thereof; a gallery

3 which has a reduced lower end that is screwed into the upper end of the reservoir and carries an outer wick tube 4 that is spaced from and concentric with the inner wick tube 2; and a flame spreader 6 that is 60 supported above the wick tubes and has its lower end extending downward into the inner tube where it has a separable connection with the usual spider 8.

A tubular wick 10 surrounds the inner 65 wick tube 2, and at its upper end is guided between the inner and outer wick tubes, the same being limited in its upward movement by the flange 11 of the flame spreader; the flame spreader, in turn, being limited against 70 undue upward movement through an interlocking engagement with the spider 8. A carrier 12 is attached to the wick for co-operation with the star wheels 13 of the wick raising spindle 14 which may be rotated 75 within its bearing 15 by means of the operating handle or wheel 16, secured to the outer end of the spindle.

The wick is split upward from its lower end, as indicated at 18, so that the opposite 80 sides of its lower end may spread out and lie upon the bottom of the reservoir; for it is obvious that without splitting the wick in this manner it would descend until its lower end engaged the bottom of the reservoir and 85 practically no farther. Wicks of the character used in oil stoves and lamps are naturally more or less stiff, and their tendency to retain a given shape or condition is increased when they become oil soaked. Let it be 90 imagined therefore that, with the wick flared out as indicated, it is elevated by the wick raising mechanism until its lower end is withdrawn from the oil supply. With all indications that an ample supply of oil is in 95 the reservoir, the flame would become smoky for want of oil and the wick would be charred and rapidly burned away. To avoid this difficulty, I employ the wick restricting means which I shall now describe. 100

In its present form, my wick restricting means is made of a single piece of wire, bent to form a ring 20 and from diametrically opposed portions of which fingers 21 depend. Of course any desired number of 105 such fingers may be employed. The ring 20 occupies the extreme upper end of the reservoir 1 and surrounds the inwardly projecting neck 23 thereof, the ring being connected, as by soldering, to the reservoir at vari- 110

ous points, as indicated at 24, one of such connections, as the one at the upper side of Fig. 2, serving as a fastening means for the ends of the wire whereof the restricting means is formed. As indicated in Fig. 1, the fingers 21 extend downward and then inward reasonably close to the wick and at their lower ends are flared outward in proximity to the bottom of the reservoir in such a way as not to interfere with the raising and lowering of the wick but so as to effectually restrict it to a course close to the bottom of the reservoir so that at all times it will be submerged in any oil contained within the reservoir.

While the herein described form of my invention is very effective and wholly satisfactory, it will be understood that I do not limit myself to this particular modification but regard my invention as covering any means of this nature which falls within the scope of the claims annexed hereto.

Having thus described my invention, what I claim is:

- 25 1. A wick restricting means for use with liquid fuel burners of the type wherein tubular wicks are supported on wick tubes and including mechanism for raising and lowering the wicks along the tube, said restricting means consisting of spaced members opposed to the wick tube and situated in proximity to the bottom of the fuel reservoir for retaining a portion of the wick adjacent thereto.
- 30 2. A wick restricting means for use with liquid fuel burners of the type wherein tubular wicks are supported on wick tubes and including mechanism for raising and lowering the wicks along the tubes, said restricting means comprising fingers carried by the burner structure and extending downward alongside the wick in spaced relation to the wick tube and into close proximity to the bottom of the reservoir for retaining portions of the wick adjacent thereto.
- 35 3. A wick restricting means for use with liquid fuel burners of the type wherein tubular wicks are supported on wick tubes and including mechanism for raising and lowering the wicks along the tubes, said restricting means comprising a member surrounding the wick and having separate portions spaced apart about the wick in opposed relation to the wick tube and in proximity to the bottom of the reservoir for retaining portions of the wick adjacent thereto.
- 40 4. A wick restricting means for use with liquid fuel burners of the type wherein tubular wicks are supported on wick tubes and including mechanism for raising and lowering the wicks along the tubes, said restricting means comprising a ring surrounding the wick and attached to the upper end of the reservoir and having fingers extending downward alongside the wick and into close proximity to the bottom of the reservoir for engaging and retaining portions of the wick near the bottom of the reservoir.
- 45 5. A wick restricting means for use with liquid fuel burners of the type wherein tubular wicks are supported on wick tubes and including mechanism for raising and lowering the wicks along the tubes, said restricting means comprising an annular member surrounding the wick and attached to the upper end of the reservoir, and depending fingers formed by loops of the wire which extend downward alongside the wick into close proximity to the bottom of the reservoir for engaging and restricting portions of the wick adjacent thereto.
- 50 6. A wick restricting means for use with liquid fuel burners of the type wherein tubular wicks are supported on wick tubes and including mechanism for raising and lowering the wicks along the tubes, said restricting means comprising a member surrounding the wick and having separate portions spaced apart about the wick in opposed relation to the wick tube and in proximity to the bottom of the reservoir for retaining portions of the wick adjacent thereto.
- 55 7. A wick restricting means for use with a liquid fuel burner of the type having a wick supporting tube and mechanism for reciprocating a tubular wick along said tube, said restricting means comprising a member carried by the burner structure and depending alongside the wick in spaced relation to the wick tube and into close proximity to the bottom of the fuel container for retaining a portion of the wick adjacent thereto.

In testimony whereof, I hereunto affix my signature.

LEE S. CHADWICK.

25 1. A wick restricting means for use with liquid fuel burners of the type wherein tubular wicks are supported on wick tubes and including mechanism for raising and lowering the wicks along the tube, said restricting means consisting of spaced members opposed to the wick tube and situated in proximity to the bottom of the fuel reservoir for retaining a portion of the wick adjacent thereto.

30 2. A wick restricting means for use with liquid fuel burners of the type wherein tubular wicks are supported on wick tubes and including mechanism for raising and lowering the wicks along the tubes, said restricting means comprising fingers carried by the burner structure and extending downward alongside the wick in spaced relation to the wick tube and into close proximity to the bottom of the reservoir for retaining portions of the wick adjacent thereto.

35 3. A wick restricting means for use with liquid fuel burners of the type wherein tubular wicks are supported on wick tubes and including mechanism for raising and lowering the wicks along the tubes, said restricting means comprising a member surrounding the wick and having separate portions spaced apart about the wick in opposed relation to the wick tube and in proximity to the bottom of the reservoir for retaining portions of the wick adjacent thereto.

40 4. A wick restricting means for use with liquid fuel burners of the type wherein tubular wicks are supported on wick tubes and including mechanism for raising and lowering the wicks along the tubes, said restricting means comprising a ring surrounding the wick and attached to the upper end of the reservoir and having fingers extending downward alongside the wick and into close proximity to the bottom of the reservoir for engaging and retaining portions of the wick near the bottom of the reservoir.

45 5. A wick restricting means for use with liquid fuel burners of the type wherein tubular wicks are supported on wick tubes and including mechanism for raising and lowering the wicks along the tubes, said restricting means comprising an annular member surrounding the wick and attached to the upper end of the reservoir, and depending fingers formed by loops of the wire which extend downward alongside the wick into close proximity to the bottom of the reservoir for engaging and restricting portions of the wick adjacent thereto.

50 6. A wick restricting means for use with liquid fuel burners of the type wherein tubular wicks are supported on wick tubes and including mechanism for raising and lowering the wicks along the tubes, said restricting means comprising a member surrounding the wick and having separate portions spaced apart about the wick in opposed relation to the wick tube and in proximity to the bottom of the reservoir for retaining portions of the wick adjacent thereto.

55 7. A wick restricting means for use with a liquid fuel burner of the type having a wick supporting tube and mechanism for reciprocating a tubular wick along said tube, said restricting means comprising a member carried by the burner structure and depending alongside the wick in spaced relation to the wick tube and into close proximity to the bottom of the fuel container for retaining a portion of the wick adjacent thereto.

In testimony whereof, I hereunto affix my signature.

LEE S. CHADWICK.
